CLAIM

The ornamental design for a grip for a climbing pole, as shown and described.

DESCRIPTION

FIG. 1 is a top perspective view of a grip for a climbing pole; FIG. 2 is a bottom perspective view of the grip shown in FIG. 1;

FIG. 3 is a top plan view of the grip shown in FIG. 1; FIG. 4 is a bottom plan view of the grip shown in FIG. 1; FIG. 5 is a front elevation view of the grip shown in FIG. 1; FIG. 6 is a rear elevation view of the grip shown in FIG. 1; FIG. 7 is a left-side elevation view of the grip shown in FIG. 1;

FIG. 8 is a right-side elevation view of the grip shown in FIG. 1; and,

FIG. 9 is a top perspective view of the grip shown in FIG. 1, showing the environment in accordance with an embodiment.

The broken lines represent environmental subject matter of an exemplary grip for a climbing pole and form no part of the claimed design.
